UNITED STATES PATENT OFFICE.

HENRY CASEVITZ, OF PARIS, FRANCE.

PRINTING-TELEGRAPH.

SPECIFICATION forming part of Letters Patent No. 727,089, dated May 5, 1903.

Application filed October 10, 1901. Serial No. 78,241. (No model.)

To all whom it may concern:

Be it known that I, HENRY CASEVITZ, a citizen of the Republic of France, residing in Paris, France, have invented certain new and 5 useful Improvements in Printing Telegraphy, of which the following is a specification.

The apparatus hereinafter described, which I have named "teletype," can be used either for transmission of printed messages by means 10 of a single wire, the impression being made on a strip or sheet of paper, or for writing in the usual manner of writing-machines. It acts on the following principle:

Principle.—It is known that the system of 15 binary numeration—that is to say, that having "2" for its base—requires only two numerals "0" and "1" and that by a greater or less number of these numerals we can represent all the natural numbers. Thus "1" is written 20 ten "1," "2" is written "10," "3" is written "11," "4=2²" is written "100," "8=2³" is written "1000," "16=2⁴" is written "10000," "32=2⁵" is written "100000," "63" is written 25 "111111." If then we have six different organs each capable of taking two different positions, which we here term the two positions "0" and "1," we see that with these six organs we can produce sixty-four different combinations corresponding to the natural numbers from "0" to "63," inclusive. 30 These combinations are respectively

000000	000001	000010
000011	000100	000101
000110	000111	001000
"	"	"
111101	111110	111111

The accompanying drawings are different views of a teletype.

40 Figure 1 is an internal view showing the mechanism. Fig. 2 is a plan, and Fig. 3 is a front view, various details being omitted for the sake of clearness. Figs. 4 to 10, inclusive, show separately the registering organs the relative movements of which produce the relative shifting of the printing-roller. Fig. 11 is a perspective diagram illustrating the action of the various mechanical organs, and Fig. 12 is a diagram showing the 45 electrical connections. Fig. 13 is a diagrammatic perspective view of an apparatus simplified for telegraph-offices. Figs. 14 and 15

show an arrangement of the manipulating-keys in the case of a machine for writing arranged as in Figs. 1 and 12. Figs. 16 and 17 55 show straight keys for the same purpose. Fig. 18 is a diagram of the installation, and Fig. 19 shows the distribution of the conducting-blades on which the transmitting-keys act. Fig. 20 is a longitudinal section of the 60 register. Figs. 21 and 22 are diagrams of parts hereinafter referred to. Fig. 23 is a diagram similar to Fig. 18, showing the parts in another position. Fig. 24 is a diagram of the installation of Fig. 21. Figs. 25 and 26 65 are face and rear edge views, respectively, of one of the drums.

In the teletype the receiving-organs are polarized electromagnets 1 2 3 4 5 6, the armatures 7 8 9 10 11 12 of which can take two positions. The position of rest, which is also 70 that when a negative current passes, corresponds to the numeral "0" and the position when a positive current passes and when the armature is attracted to the magnet corresponds to "1."

As above explained, each of the magnets corresponds to an order of unity of the binary system of numeration.

Register.—The name "register" is applied 80 to the combination of organs which register the positions of the armatures. The register comprises a spindle 13, and it being understood that each sixty-fourth part of a revolution of this spindle corresponds to a unit of 85 the first order in the binary system, then when the magnet 1 acts the spindle 13 turns one unit of the first order—namely, one sixty-fourth of a revolution. On the action of magnet 2 the spindle 13 turns a unit of the second order—that is to say, spindle 13 turns a unit $\frac{2}{64} = \frac{1}{32}$ of a revolution. Magnet 3 acting, spindle 13 turns a unit of third order, $\frac{4}{64} = \frac{1}{16}$. Magnet 4 acting, spindle 13 turns a unit of fourth order, $\frac{8}{64} = \frac{1}{8}$. Magnet 5 acting, 90 spindle 13 turns a unit of fifth order, $\frac{16}{64} = \frac{1}{4}$. Magnet 6 acting, spindle 13 turns a unit of sixth order, $\frac{32}{64} = \frac{1}{2}$. Thus to produce twenty-five sixty-fourths of a revolution will require the release of magnet 5, which produces sixteen sixty-fourths of a revolution; magnet 4, which produces eight sixty-fourths of a revolution, and magnet 1, which produces one sixty-fourth of a revolution. When these

three magnets are energized, the total movement of the shaft will represent the sum of the lengths of the slots in the several corresponding drums. A type-wheel on the shaft 5 and on which the characters are separated by one sixty-fourth of a circumference will accordingly rotate to the desired point. The correspondence between the number "011001" and the energizing of the magnets 1, 4, and 5 10 will be seen by observing that the first, fourth, and fifth characters of this number are of one kind, representing the three magnets which are energized, while the other characters are of the opposite kind, representing the magnets which are not energized.

Operation of spindle 13.—Clockwork (not shown on the drawings in order to avoid complication) tends to turn the spindle 13 in the direction of the arrow. A drum 14 is keyed 20 on 13, and five other drums—15 to 19, inclusive—are mounted loosely on 13, each carrying a disk of different diameter from its drum, disk 20 on 15, 21 on 16, 22 on 17, 23 on 18, and 24 on 19. A disk 25 is also loose on 25 the shaft, but carries a pawl 29, engaging a long groove in the drum 19, so as to arrest said drum when the latter has made thirty-two sixty-fourths of a revolution. The organs which work drum 14 are mounted on 20. 30 The organs which work drum 15 are mounted on 21. The organs which work drum 16 are mounted on 22. The organs which work drum 17 are mounted on 23. The organs which work drum 18 are mounted on 24. The organs which work drum 19 are mounted on 25. I have therefore shown separately in Figs. 4 to 10, inclusive, how these drums and disks are arranged. Clockwork tends to turn the spindle 13, and consequently the drum 14, in 40 the direction of the arrow; but this drum is stopped by a pawl 26, carried by the disk 20 and engaging a stop 27, extending only partially across the drum, as shown in Figs. 25 and 26. The drum 14 has a groove 28 (similar to 32, Fig. 26) lying alongside and out of line with the stop 27 and pawl 26, as indicated, so as to pass the pawl in returning to zero, as hereinafter described, in which engages a second pawl 29, also carried on 20. 45 The electromagnet 1, by attracting its armature 7, can disengage the pawl 26 from the stop 27. When the magnet 1 acts, it withdraws the pawl 26, and the drum 14 thus freed turns in the direction of the arrow until the pawl 29 reaches the end of the groove 28. Two springs 30, carried also by the disk 20, press the pawls 26 and 29 against the drum 14. The groove 28 in the drum 14 allows the disk 20 to turn one sixty-fourth of 55 a revolution relatively to the shaft and the drum 14. The other drum 15 and disk 21 are similarly arranged; but the groove 31 in the drum 15 allows it to turn one thirty-second of a revolution. In like manner the groove 60 32 of 16 allows it to turn one-sixteenth of a revolution, the groove 33 of 17 allows it to turn one-eighth of a revolution, the groove

34 of 18 allows it to turn one-fourth of a revolution, the groove 35 of 19 allows it to turn one-half of a revolution. The disk 25 is normally held fixed, so that until the pawl 36 is withdrawn it cannot move, but the shaft 13 may rotate within it. That being understood, it is clear that the drum 19 cannot revolve until the magnet 6 is energized, the drum 18 cannot revolve until the magnet 5 is energized, and so on to the end; but if any one of the magnets is energized all the drums between the drum corresponding to such magnet and the drum 14, including the latter, 80 can turn through an arc depending on the length of the groove therein. Thus it is seen that whenever the magnet 1 acts the drum 14 is freed, and consequently the spindle 13 turns one sixty-fourth; when magnet 2 acts, 85 freeing drum 15, spindle 13 turns one thirty-second; when magnet 3 acts, freeing drum 16, spindle 13 turns one-sixteenth; when magnet 4 acts, freeing drum 17, spindle 13 turns one-eighth; when magnet 5 acts, freeing drum 18, 90 spindle 13 turns one-fourth; when magnet 6 acts, freeing drum 19, spindle 13 turns one-half. The disk 25 is normally held in a fixed position by the armature 36 of the magnet 37. It is thus seen that the movement of each of 95 the drums 14 to 19, inclusive, corresponds to a shift through an angle proportional to the units of the first, second, third, fourth, fifth, and sixth order in the binary system and that by energizing the magnets 1 to 6, inclusive, 100 angular movements of the spindle 13 are obtained corresponding to units of the several orders.

If, for instance, a shift of twenty-five sixty-fourths of a revolution were desired, since 105 "25" is written in the binary system as "011001," it is sufficient to energize the magnets 1, 4, and 5. In like manner a shift of forty-seven sixty-fourths is effected by energizing the magnets 1 2 3 4 6, since "47" is 110 written "101111."

Type-wheel.—The spindle 13 is connected to a type-wheel having on its circumference sixty-four different characters, any one of which can be brought to one place by the action of the magnets 1 to 6.

Return of register to zero.—In this position of the type-wheel some of the drums 14 to 19, inclusive, are held by their pawls 26 and some by the pawls 29. Those which have been 120 moved and are held by the pawls 29 must then be restored to their original position. In this restoration I use a fixed rod or bar 44, Figs. 1 and 4 to 9, in the following manner: The magnet 37 is energized and the disk 25 125 is freed, and thereupon the spindle 13 and the other drums make a complete revolution and the tails 38 to 43, inclusive, of the pawls 29 are brought against the rod 44. If we suppose that the drum 15 is held by its pawl 26 130 in its original position with relation to the drum 16, then the pawl 39 on striking the rod 44 will be merely raised and allowed to return into the groove when the rod 44 has been

passed. If we suppose now that the drum 16 has moved from its original position with relation to the drum 17, so that the pawl 40 has reached the rear end of the groove 32, then this pawl on striking the rod 44 is raised and is held in its raised position, the drum 16 is freed from the drum 17 and is moved by the clockwork driving the spindle 13 turning until its pawl 26 engages the stop 27, and at this moment the drum 16 will turn the disk 22, and with it the pawl 40, causing it to pass 44 and drop into its groove 32, thus restoring the parts to their original positions. In the turning of the drum 16 the narrow groove 32, Figs. 25 and 26, passes freely alongside the pawl 26 without engaging the latter, the pawls 26 and 40 and the corresponding grooves being out of line with each other, as shown. Thus it appears that by the action of the single magnet 37 and the rod 44 all the pawls 26 are made to engage the stops 27, the spindle 13 and the drums being brought to their initial position.

The register is the chief organ of the teletype. It may be modified by increasing or diminishing the number of electromagnets. It has many applications. Hereinafter are described teletypes for private use; also, teletypes for office work.

Teletype for Private Use.

Receiver.—This apparatus is shown diagrammatically in Figs. 11 and 12 and as constructed in Figs. 1, 2, and 3. It is a machine for writing at a distance and can also serve as an ordinary writing-machine. The register is arranged in the lower part and works a bevel-wheel 45, which gears with another equal bevel-wheel 46, which by a spindle 47, provided with a universal joint, works a type-wheel 48, which has a square hole fitting on a square vertical axis 49, which is connected by a universal joint with 47 and which may slide up or down in the type-wheel 48 as the type-wheel moves laterally. The type-wheel 48 is carried on a carriage having four wheels 50 running on rails 51 and a rack 52. The carriage, with the type-wheel and rack, moves in front of a roller 53, on which can be placed a sheet of paper held by small rollers 54. A spiral spring 55, inclosed in a barrel, (shown only in Fig. 3 in order to avoid complication of the drawings,) strains a cord 56, which tends always to draw the carriage toward the left. The rack 52 gears with a wheel 57, on the axis 58 of which, termed the "impression-axis," is mounted a second wheel 59, having as many teeth as 52, and a second wheel 60, also having the same number of teeth and furnished with a pawl 61. A second axis 62, termed the "manipulating-axis," parallel to the former, carries, first, a wheel 63, having a single tooth gearing with 59; secondly, a wheel 64, provided with a notch 65 and a projection 66; thirdly, a ratchet-wheel 67 68, worked by an anchor 69; fourthly, a brush 70, moving over a fixed circle of insulated

sectors 71; fifthly, a clockwork, (not shown in the drawings,) which tends to turn the manipulating-axis in the direction of the arrow. Finally, the roller 53 is mounted on a frame 72, which can be pushed by the projection of the wheel 64 so as to produce contact of the roller with the type-wheel, and consequently the impression of the character presented to the roll on the paper. The double ratchet-wheel 67 68 consists of two ratchets, each having six teeth arranged on six-eighths of their circumference, so that when they have been turned six-eighths of a revolution they turn the other two-eighths of themselves by reason of the clockwork referred to. The circle of sectors 71 comprises six sectors, likewise arranged over six-eighths of its circumference and corresponding to the six-eighths of a revolution made by the teeth of the ratchet-wheels.

The machine operates as follows: It takes place in eight periods. At each of the periods one to six there arrives by line a current now +, now —, which acts on the polarized relay 73. (See Fig. 12.) This relay sends a current of the same sign as that received on the one hand to the electromagnet 74, which works the anchor 69, and on the other hand to the brush 70, which is bearing on one of the sectors 71. The first of these sectors is connected to the electromagnet 1, the second to magnet 2, and so on. The local current sent by the brush 70 actuates successively each of the magnets when the current received is positive, but does not actuate them when the current is negative, the magnets being polarized for this purpose. At the end of the sixth period the register and consequently the wheel 45, have taken a position corresponding to the order in which the six currents from the line have followed each other. At the same time at each of the six periods the ratchet-wheel 67 68 has advanced a tooth, and consequently the brush 70 a sector. At this moment the anchor faces the part which has no teeth and the ratchet-wheel by itself moves over the remaining two-eighths. At the seventh period the projection 66 of the wheel 64 bears against the frame 72 and produces the impression. At the eighth period the single tooth of the wheel 63 engages 59 and moves it one tooth around, along with 51 and 52, and at this moment the electric circuit, battery 77, brush 75, wheel 63, wheel 59, brush 76, electromagnet 37, and battery 77 is closed by the teeth of 63 and 59, which are engaged, and the register is brought back to its initial position, as has been explained.

The recoil or return of the type-wheel to the beginning of a new line and the advance of the paper for such new line are automatically effected by contact of the terminals 78 and 79 on the register-wheel with terminals 88 80 and 80 81 on the frame 72.

Recoil.—We have seen that at each revolution of the axis 62 the wheels 59 and 60, and

consequently the rack and the type-wheel, 1
advance one step. When the type-wheel has
thus reached the end of a line, it has to be
moved back, and this for a certain position
5 of the register, which may be termed the "re-
coil" position. Two pins 78 and 79 on the
wheel 45 present themselves to contacts 88
and 80 or 80 and 81. At the seventh period—
that is to say, when the projection 66 rocks the
10 frame 72—88, 80, and 81 and at the same time
88 come in contact with 78, and 80 in contact
with 79, and the circuit of the local battery
is closed, as follows: battery 77, magnet 82,
magnet 83, contacts 84 85 (these terminals 84
15 and 85 being normally in contact, as hereinafter
explained) 88 78 79 80, battery. The
armature 133 of magnet 82 has an upwardly-
projecting tooth or pawl 85, Figs. 2, 11, and
22, adapted to enter a notch 65, and thus stop
20 the axis of manipulation. A spring 134 holds
the pawl out of the notch when the magnet
is not energized. The magnet 83 attracts
its armature and releases the pawl 61 from
the teeth of wheel 60, so that the rack thus
25 freed recoils under the action of the spring 55.
The two contacts 84 85', Fig. 12, are placed on
the frame of the teletype. A projection 128
from the rack, when the carriage reaches the
30 end of its stroke to the right, breaks the con-
tact of 84 and 85', and consequently opens
the circuit of battery 77, magnet 82, magnet
83, contacts 84 85' 88 78 79 80, battery.
The magnets 82 and 83 release their ar-
35 matures, the tooth 61 engages the teeth of the
wheel 60, the magnet 83 releases the axis of
manipulation, which, continuing its revolu-
tion in the eighth period, brings the register
back to its initial position.

New line.—For a certain position of the
40 register-wheel the pins 78 79 come to face 81
and 80 and put them in communication in
the seventh period, making the following cir-
cuit: battery, magnet 89, contacts 81 79 78 80,
battery. The magnet 89, attracting its ar-
45 mature 90, acts on the rod 91, which causes
the ratchet-wheel 92 to turn one tooth, and
with it the roller 53.

Transmitter.—I have studied various sys-
tems of transmitting, which are shown in
50 Fig. 1 and in Figs. 14 to 18, inclusive. In
principle in order to print a certain character
it is sufficient to send into line six successive
short currents, the directions of which de-
pend on the character. If, for instance, we
55 wish to transmit the thirty-eighth character
on the type-wheel, since in the binary sys-
tem 38 is written "100110," the successive
currents to be sent are + - - + + -. The
transmitter consists of keys each correspond-
60 ing to one of the characters. Each key car-
ries a rubbing contact which when the key is
depressed rubs successively over six blades,
each of which is connected to one of the poles
of a double battery, the middle element of
65 which is connected to earth. The rubbing
contact, therefore, receives six successive cur-
rents, which are sent to line, and conse-

quently to the receiving-station. When the
key reaches the end of its stroke, it breaks
the connection of the rubber with the line 70
and is then raised by a spring. On reaching
the end of its upstroke it reestablishes the
connection of the rubber to the line, which is
then ready to act again. In other kinds of
75 keys, which I prefer and which I shall de-
scribe, the downward movement of the key
makes no communication between the rub-
ber and the line which is effected by its re-
turn stroke. The keys shown in Fig. 1 and in
80 Figs. 14, 15, and 16 are of this kind. 93 is the
contact-rubber. 94 and 95 indicate two con-
tact-springs which close the circuit when the
key 96 is at the extreme of its downstroke. 97
is the return-spring. 98 and 99 are two tap-
85 plets which when struck by the key-lever raise
and lower the rod 100, which makes and breaks
the contacts 94 95. Fig. 16 shows a direct
key without lever. 101 is the contact-rub-
ber. 102 103 are the contacts, alternately
closed and opened by the rod 104. The key 90
is returned by the spring 105. Fig. 17 shows
a piston-key in which the compression and
expansion of the air in the cavity 106 effects
the opening and closing of the contacts 102
103 by the rod 104. Figs. 18 and 23 show 95
also diagrammatically the mounting of the
transmitter with the relay 74 and the two le-
vers for transmission and reception 107 and
for transmission in writing 108 and finally
an inversion-key 109, the use of which I shall
hereinafter describe.

Inversion-key.—In order to simplify the ar-
rangement of the transmitter the sixty-four
signals have been reduced to thirty-two by
grouping the signals in pairs in such a man-
ner that each may, so to speak, be the com-
plement of the other—that is to say, that the
positive current of the one corresponds to a
negative current of the other. Thus the sig-
nal "011010," or $- + + - + -$, has for its
complement "100101," or $+ - - + + +$. The
inversion-key changes the direction of
the current given by the transmitting-battery,
and thus converts a signal into its comple-
ment. Fig. 19 shows diagrammatically the
arrangement of the blades relatively to the
battery, as well as that of the inversion-key
109. The special lever 107 connects the trans-
mitter and receiver of each apparatus and al-
lows change from the receiving to the trans-
mitting position. A second lever 108, Figs.
18 and 23, allows of sending to earth instead
of to line the current issuing from the re-
ceiver during transmission. In these condi-
tions the machine serves simply for writing.

The several parts shown in Figs. 18 and 23
operate as follows: The contacts 150 to 155,
corresponding to each character, are connect-
ed to the battery through the inversion-key
109. Any one of the several types of finger-
keys may be used. That shown in Fig. 23
comprises a rod 156, which carries at its base
a cylinder 106, carrying lateral spring-termi-
nals 157. A piston 159, furnished with a rod

154, slides in the cylinder 106, the outer end 158 of the rod being of insulating material; but the body thereof is of conducting material. A plate is arranged below the lower end 5 of the rod and carries a pair of spring-terminals 102 103, the space between which is adapted to be bridged by the conducting portion of the rod 104, and which terminals through the keys 107 108 are connected either to the line or 10 to the earth, according as the apparatus is to serve as a telegraph or a writing machine. When the key 105 is pressed, the spring 157 passes in succession over the several contacts 150 to 155; but no current passes, because 15 there is a break between the rod 104 and the terminals 102 103. When the key is near the end of its downward movement, the air contained between the top of the cylinder 106 and the piston 159 becomes sufficiently compressed to bear on the piston and force the end of its rod between the springs 102 103, thus connecting it to the line, so that as the key rises under the action of the spring 105 the terminal 157 again passes successively 20 over the contacts 155 to 150 and this time successively connects the line with each of these contacts. When the key is raised nearly to the limit of its upper movement, the piston is engaged by the lower end of the cylinder 106, and the rod is separated from the terminals 102 103, thus restoring the parts to 25 their original position.

The key 107 has two purposes: first, it puts into the circuit or cuts out from the circuit 30 the transmission-keys, so as to permit of transmission or reception of messages; second, it causes the current to pass always in the same direction through the electromagnet 74 whatever be the operation—that is to say, whether 35 it be transmission or reception. The key 107 operates simultaneously four switch-plates 160 to 163, which operate between eight contacts 164 to 171. When the key is raised, Fig. 18, which is the position for the reception 40 of messages, the sending-keys being cut out, the current comes from the line and passes in succession through key 108, 170, 163, 172, magnet 74, 173, 162, 168, 160, 164, 166, 161, to earth. If the current is positive, as 45 determined at the sending end of the line, it traverses the magnet 74 in the direction 172 173, and in the opposite direction if it is negative. When the key is pressed down, Fig. 50 23, for the sending of messages, the current passes from the battery by the intermediation of the sending-key 105 and then by way of 103, 165, 160, 171, 163, 172, magnet 74, 173, 162, 169, and key 108 to the line. In this 55 case, as in receiving, the plus current traverses the magnet 74 in the direction 172 173, so that the key 107 determines that the positive current shall always pass through the magnet 74 in the same direction.

The key 108 operates a single plate 174, connecting at one side to a line-terminal 175 and at the other side to a ground-terminal 176. When it is raised, as shown, the line is

in direct communication with the key 107 for reception or transmission of messages. By lowering the key the blade 174 connects with 70 the earth-terminal 176. In this position the circuit coming from the key 107 being supposed in position for transmission, a current may be sent from the battery through the magnet 74 and to ground without traversing 75 the line, the circuit from the key 107 passing directly through 174 and 176 to earth. Being thus disconnected from the distance-line, the apparatus serves as a writing-machine.

The key 109 is a simple inversion-key for 80 two wires. When this key is pressed down, all the contacts of the group 150 to 155, which are connected normally to the positive pole of the battery, become connected to the negative pole, and inversely. This key allows of 85 reducing the number of keys employed to one-half that which would be necessary without it, each sending-key being capable of sending into the line two combinations of signals, one with the key 109 raised, the other 90 with the same key lowered.

The keys are arranged in three rows, each of ten, numbered from left to right. Two keys 112 113 at the lower part of the board correspond to the blank and the period and to the 95 recoil and change of the line.

The following table indicates, merely by way of example, how I establish correspondence among the different keys and their representation in the binary system, as well as 100 the corresponding characters.

Inversion-lever raised.					Inversion-lever down.			105
Rows.	Keys.	Bi-nary.	Deci-mal.	Char-acters.	Bi-nary.	Deci-mal.	Char-acters.	
1	1	111111	63	a	000000	0	A	110
	2	111110	62	z	000001	1	Z	
	3	111100	60	e	000011	3	E	
	4	111101	61	r	000100	2	R	
	5	111001	57	t	000110	6	T	
	6	111000	56	y	000111	7	Y	
	7	111010	58	u	000101	5	U	
	8	111011	59	i	000100	4	I	
	9	110011	51	o	001100	12	O	
	10	110010	50	p	001101	13	P	
2	1	100000	48	q	001111	15	Q	115
	2	110001	49	s	001110	14	S	
	3	110101	53	d	001010	10	D	
	4	110100	52	f	001011	11	F	
	5	110110	54	g	001001	9	G	
	6	110111	55	h	001000	8	H	
	7	100111	39	j	011000	24	J	
	8	100110	38	k	011001	25	K	
	9	100100	36	l	011011	27	L	
	10	100101	37	m	011010	26	M	
3	1	100001	33	x	011110	30	X	120
	2	100000	32	c	011111	31	C	
	3	100010	34	v	011101	29	V	
	4	100011	35	b	011100	28	B	
	5	101011	43	n	010100	20	N	
	6	101010	42	6	010101	21	2	
	7	101000	40	7	010111	23	3	
	8	101001	41	8	010110	22	4	
	9	101011	45	9	010010	18	5	
	10	101100	44	,	010011	19	1	
4	1	101110	46	line	010001	17	blank	125
	2	101111	47	line	010000	16	recoil	

Hence the characters are arranged on the type-wheel thus: "A Z R E I U T Y H G D 13c F O P S Q recoil blank 5 1 N 2 4 3 J K M L B V X C c x v b l m k j 7 8 6 n , 9 . line q s p o f d g h y t u i e r z a."

The apparatus for telegraph-offices is shown:

diagrammatically in Fig. 13. It is greatly simplified, for it has none of the special provisions for writing on paper. It comprises only a register 110, having on it a type-wheel 111. A paper strip 114 moves under 11, and a roller 87 presses it, when required, against 11. The impression-axis is dispensed with. There remains only the axis of manipulation 115, carrying two wheels 116 117, the ratchet-wheels 118 119 and the brush 120 moving over the sectors 121. Two sets of clockwork (not shown) actuate the register and the axis of manipulation. The relay 122, like that in the private apparatus, takes a local current 15 instead of the line-currents.

The periods one to six are still employed for the action of the register by the seven electromagnets, and at the seventh the impression is produced by the action of the projection 123 on the lever 124, which carries the roller 87. At the eighth period the paper is moved onward by the turning of the rollers 125 and consequently the advance of a strip by the single tooth 126 of the wheel 116. At 25 the same time the contact 127, which closes the circuit of the magnet 37, (for moving the register back to zero,) is actuated by the projection 123.

The transmitter consists merely of a double-contact key.

The alphabet is simply like a Morse code, every character, however, consisting of six signals. The transmitter may also consist of a set of six double-contact keys combined 35 with a distributer which sends successively into line positive or negative currents, according to the position of the several keys. The diagram Fig. 21 illustrates the arrangement of the circuits for such a transmitter, 130 40 being the brush, and 131 the sectors, of the distributer and 132 being the double-contact keys. The currents are received in the same order and translated, as has been explained. In order to simplify the figure, there is represented only the group of six keys and the brush and its six contacts. The axis of the brush 130 is connected to the line similarly to the transmitters previously described by means of a key, such as 107, a magnet 174, 45 and a key 108. (Not represented in this figure, but shown in Figs. 18 and 23.) In order to show the general arrangement of the system where the transmitter of Fig. 21 is employed, I have added a diagram Fig. 24. It 55 is apparent by a simple inspection of Figs. 21 and 24 that the transmitter is composed of six keys 132, each connected to one of the blades of the distributer 131. Normally each key is raised and is connected by its upper 60 contact with the positive pole of the double battery, the center of which is connected to earth. By lowering one or more of the keys they may contact with their lower terminals, connected to the negative pole of the 65 battery. A clock-movement turns continually the brush 130, which thus successively

puts the line in contact with the different sectors of the distributer 131, and consequently with the keys and with the battery. All the raised keys thus send into the line a 70 positive current and all the lowered keys a negative current. By lowering one or more keys the proper currents for a desired combination of signals can be sent into the line. This general arrangement is well known and 75 is only claimed here in its application to my system.

Compared with systems of transmission founded on the same principle my system has the important advantage of dispensing entirely with the synchronism necessary for printing apparatus employed in telegraphy. 80

The operation of the several elements of the apparatus having been described in detail, I will describe briefly the operation of 85 the whole, referring especially to Figs. 1 to 12. The current coming from the line sets in operation the drums to turn the pinions 45 46, which control the type-wheel 48. The pinions and the type-wheel are connected by 90 a rod furnished with two universal joints and terminating in a square portion 49, which slides in a square socket provided in the center of the wheel 48. This sliding connection furnishes the necessary facility for moving 95 the wheel to greater or less distance from the lower point of its driving-shaft. The necessary drums having been operated, the type-wheel turns to the proper angle to present a determined letter in front of the roller 53. 100 Then the ratchet-wheels 67 68 receive their rotary movement, carrying their axis. The projection 66 of the wheel 64, mounted on this axis, bears against the frame 72, as seen best in Fig. 11, and thus produces the impression. The operating-shaft continuing its rotation, the wheel 63 engages the wheel 59, turning a distance of one tooth the carriage which carries the type-wheel and at the same time closing an electric circuit, which 105 sends a current through the electromagnet 37 to carry the type-wheel around to its starting-point. The backward return of the type-wheel carriage at the end of each line is accomplished by the sending of a particular 110 signal which stops the operating-shaft of the machine by means of the electromagnet 82 and at the same time frees the shaft, which causes the travel of the type-wheel carriage by means of the electromagnet 61, thus permitting the return of the carriage under the action of the spiral spring wound around the barrel 55. The electromagnets 61 and 82 are released by the breaking of the current at 84 and 85 produced by the movement of the 115 bridge 128, which is carried by the type-wheel carriage, Fig. 12. The change of the line occurs also by the sending of a particular signal which produces a local current in the electromagnet 89, which by means of the lever 120 90 and rod 91 acts on the pinion 92, carried 125 by the shaft of the carriage 53.

Having thus described the nature of this invention and the best means I know of carrying the same into practical effect, I claim—

1. In a signal-transmitting system, the combination of a series of electromagnets, a registering apparatus composed of a series of drums, a rotary axis upon which the first drum is keyed and upon which the subsequent drums are loose, a pawl connected to the second and each succeeding drum and normally engaging a stop in the preceding drum, an operative connection between the armatures of the several electromagnets and the several pawls respectively, whereby the energizing of each magnet releases a corresponding pawl so as to permit the drum to turn, and means for limiting the movement of the several drums to a determined angle corresponding to the character to be formed.
2. In a signal-transmitting system, the combination of a series of electromagnets, a registering apparatus composed of a series of drums, a rotary axis upon which the first drum is keyed and upon which the subsequent drums are loose, a pawl connected to the second and each succeeding drum and normally engaging a stop in the preceding drum, an operative connection between the armatures of the several electromagnets and the several pawls respectively, whereby the energizing of each magnet releases a corresponding pawl so as to permit the drum to turn, and a limiting-pawl attached to the second and each subsequent drum normally engaging a groove of determined length in the preceding drum, whereby when the first pawl is released by the energizing of the electromagnet the second pawl limits the relative rotation of the two drums through a determined angle.
3. In a signal-transmitting system, the combination of a series of electromagnets, a registering apparatus composed of a series of drums, a rotary axis upon which the first drum is keyed and upon which the subsequent drums are loose, a pawl connected to the second and each succeeding drum and normally engaging a stop in the preceding drum, an operative connection between the armatures of the several electromagnets and the several pawls respectively, whereby the energizing of each magnet releases a corresponding pawl so as to permit the drum to turn, means for limiting the movement of the several drums to a determined angle corresponding to the character to be formed, and means for operating said electromagnets comprising a current-distributer, an escapement controlling the same, an electromagnet controlling said escapement, a segmental gear carried by said escapement, a clock - movement operating said escapement and rotating said segmental gear, and means for producing impressions and moving the paper.

In witness whereof I have hereunto signed my name in the presence of two subscribing witnesses.

HENRY CASEVITZ.

Witnesses:

JULES ARMENGAUD, Jeune,
MARCEL ARMENGAUD, Jeune.

operative connection between the armatures of the several electromagnets and the several pawls respectively, whereby the energizing of each magnet releases a corresponding pawl so as to permit the drum to turn, means for limiting the movement of the several drums to a determined angle corresponding to the character to be formed, and means for returning said registering apparatus to its starting-point comprising a supplementary electromagnet adapted to be energized after the making of a signal, a pawl engaging a stop on the last drum of said series, and means operated by said electromagnet for withdrawing said pawl to permit a complete rotation of said axis.

4. In a signal-transmitting system, the combination of a series of electromagnets, a registering apparatus composed of a series of drums, a rotary axis upon which the first drum is keyed and upon which the subsequent drums are loose, a pawl connected to the second and each succeeding drum and normally engaging a stop in the preceding drum, an operative connection between the armatures of the several electromagnets and the several pawls respectively, whereby the energizing of each magnet releases a corresponding pawl so as to permit the drum to turn, means for limiting the movement of the several drums to a determined angle corresponding to the character to be formed, and means for operating said electromagnets comprising a current-distributer, an escapement controlling the same, an electromagnet controlling said escapement, a segmental gear carried by said escapement, a clock - movement operating said escapement and rotating said segmental gear, and means for producing impressions and moving the paper.
